UNITED STATES PATENT OFFICE

OTTOKAR STERN, OF VIENNA, AUSTRIA

METHOD OF FILLING PITS

Application filed July 5, 1929, Serial No. 376,055, and in Austria July 13, 1928.

This invention relates to an improved method of filling pits with an increased effect of compression by which tubular driving piles are sunk into the ground by ramming, 5 boring or flushing and by means of an inner tubing of the same the filling material is introduced into the pit during the withdrawal of the driving piles.

According to the present invention the tube 10 for the introduction of the filling material (the filling tube) is of considerably smaller diameter than the driving-tube. Thus the filling material emerges from the said tube with a head which is a multiple of the speed 15 at which the tubing is hoisted out of the soil. This follows from the law of hydraulics concerning the inverse proportion of heads and sectional areas.

If, for instance, the tubing and consequent- 20 ly the pile driven by it has a sectional area of 2200 sq. cm., while the filling tube has a sectional area of 280 sq. cm. only, their proportion is 1:8. If, now, the tubing is hoisted up at a speed of 0.5 metre per second, the 25 filling material pours out at a speed of $0.5 \times 4 = 4$ m./sec., which corresponds to a momentum of about 0.8 kgm. for each kg. of the filling material. Thus, if a 5 m. (about 17 ft.) concrete column within the filling tube of the 30 above diameter weighs about 2500 kg., this whole mass is subjected to a compression effect of 2000 kgm., which corresponds to a driving action of more than 400 blows of 5 kgm. each. This is equivalent to the process 35 of pouring the concrete in 20 cm. layers and tamping each layer with sixty heavy and powerful blows.

Of course owing to this ramming effect, the 40 wall of the pit is subjected to a displacing pressure, which more or less enlarges its sec- 45 tional area depending on the nature of the soil.

Experience has also shown that piles made according to the present invention take 10% 45 to 30% more concrete than corresponds to the cubature of the pit, which naturally results in an increased carrying capacity.

The smaller (within practical limits) the 50 proportion between the sectional areas of the driving-tube and the filling-tube, the stronger

will be the head of the filling material at the opening of the filling-tube. Theoretically this could be increased up to the speed of free drop corresponding to the height of the column formed by the filling material in the 55 filling-tube.

As already stated, the force used for the compression depends not only on the speed but also on the weight of the mass set in motion each time in the filling-tube. According 60 to the present invention the effect of compression can be regulated by varying the height of the charge-column in the filling-tube, in order to adapt the effect of compres- 65 sion to the various soils.

This effect, due to the head imparted to the filling material, increases rapidly for, as is known, it increases in proportion with the square of the speed. Thus according to the example given above, with a filling-tube of 70 half the sectional area, viz. 140 sq. cm., the head of the filling material would be 8 m./sec. and the energy per 1 kg. = 3.2 kgm., i. e. the quadruple. On the other hand, the speed at which the tubing is hoisted out of the ground 75 increases to the same extent the head of the filling material. A further feature of the present invention therefore consists in hoisting up the tubing in short lifts and each time with a sudden jerk, because greater speeds 80 in the hoisting of the tubing, at their sudden annihilation, cause a powerful pressure of the moving mass (the filling material). Concrete or any other mortar mixture, broken stones, sand, slag and the like may be used 85 as filling material.

One mode of carrying out the method according to the present invention is shown diagrammatically and by way of example in 90 the drawing.

The driving pile 1, which has been sunk for instance by ramming, is provided with a centrally disposed tubing 2 through which the filling material is introduced. The length of the tubing 2 can be suitably increased by 95 an extension tube 3. The said tubing 2 rests on a casing 4, forming the deposition compartment and at the same time the bottom end of the driving pile. The tubing is charged with filling material up to a height H accord- 100

ing to the desired effect of compression, and subsequently the driving pile is withdrawn a certain distance. The filling and withdrawing operations are carried out successively, 5 or they may overlap one another.

I claim:—

1. The method of filling pits which consists in sinking a cylindrical smooth driving pile, introducing the filling material into a filling 10 tube passing through and being of considerable smaller diameter than said driving pile, hoisting the driving pile at intervals with a sudden jerk in short lifts and abruptly stopping the hoisting motion each time in order 15 to transform the thus increased inertia of the column of material within the filling tube into enhanced pressure of the filling material in the pit below the driving pile.
2. The method as claimed in claim 1, further consisting in varying the height of the column of material within the filling tube for varying the effect of compression.

In testimony whereof I affix my signature.

OTTOKAR STERN.
